UNITED STATES PATENT OFFICE.

ERNST GUSTAV HOFFMANN, OF LONDON, ENGLAND.

DEVICE FOR FEEDING WIRE.

SPECIFICATION forming part of Letters Patent No. 624,491, dated May 9, 1899.

Application filed March 5, 1898. Serial No. 672,754. (No model.)

To all whom it may concern:

Be it known that I, ERNST GUSTAV HOFFMANN, a subject of the German Emperor, residing at London, England, have invented a certain new and useful Improvement in Devices for Feeding Wire, of which the following is a specification.

This invention relates to certain improvements in devices for feeding wire adapted for ball-cutting, screw-making, screw or nail heading, and like machines, the object of the invention being to provide devices which will feed the wire positively a regulated distance each time without slip when a high reciprocating speed is employed and which will yield when excessive pressure is brought to bear upon the parts by reason of inaccuracy in the diameter of the wire.

In carrying out the invention it has been specially designed in connection with a ball-making machine in which the wire fed to the machine is gripped and which is released at intervals, the balls being shaped from the rotating wire by means of cutters presented to it. For the purpose of illustration, therefore, the invention will be described with reference to its application to such a machine.

In the accompanying drawings, Figure 1 is a central vertical section through the clutch and feed-lever, a part being in elevation. Fig. 2 is a front elevation of same. Fig. 3 is a side elevation of the clutch, showing same closed on the wire. Fig. 4 is a similar view showing the clutch open on the wire. Fig. 5 is a detail showing in side elevation the segments which hold the wire and a collar in section for gripping same. Fig. 6 is a side elevation of the segments alone. Fig. 7 is an end elevation with the parts opened out. Fig. 8 is a plan, looking from beneath, of the feed-lever and clutch; and Fig. 9 is a side elevation of same.

The part proper which holds the wire consists of three independent segment-jaws $b b b$, which are preferably first formed in one piece and then separated by slitting with a saw. The interior diameter of these jaws is made in accordance with the wire which has to be gripped, while the exterior a is slightly tapered and fits into an internally-tapered collar c . Within the clutch-segments are turned some small grooves d , Figs. 5, 6, and 7, in each

of which is a separated ring of thin spring-wire. These springs act to force the segments $b b b$ apart and away from the wire f . 55 On the outside of the clutch-segments and located about the middle of same is another groove e , in which is also a separated ring of thin spring-wire, the object of which is merely to keep the segments $b b b$ together when they 60 are removed from the collar c , so that the handling of the segments by themselves does not entail the separation of the parts and the falling out of the small internal springs.

Upon the collar c is mounted a housing g , 65 having a flange g' , said housing being closed at one end by a nut h , screwed therein and at the other end by an inwardly-projecting flange h' , against which abuts a flange c' of the collar c . Between the flange c' and the nut h is 70 a row of balls forming a ball-bearing. The flange g' of the housing g is gripped by lugs $i i'$, rotatably held by a screw j in the yoke-arm of a feed-lever A , such arrangement enabling the lugs $i i'$ to turn slightly when the 75 lever is shifted, so that no twisting strain is put upon the clutch.

It will be seen that between the flanges h' and c' there is a common rubbing contact during the rotation of the collar c with the wire 80 when the clutch is moved in that direction to strip the collar c from the segments, while in the other direction there is a rolling contact, this side being that which has to stand the greatest pressure or that exerted by the closing of the clutch. The opposite side may, however, be provided with a ball-bearing, if 85 deemed necessary.

The operation of the feed-clutch can best be followed at Figs. 3 and 4. In Fig. 3 the 90 clutch is shown closed, which means that the functions of the machine have forced collar c through the medium of the feed-lever A and ball-bearing upon segments b . In this position the feed-clutch is ready to effect the forward motion or feed of the wire whenever called upon to do so. Fig. 4 shows this forward motion or feed of the wire having taken place and the collar driven partly off the tapered segments, and therefore entirely free 100 to revolve or to move longitudinally upon the wire by reason of springs d , which immediately separate the segments $b b b$ as soon as the collar c is withdrawn sufficiently to per-

mit said springs *d d* to act. It therefore follows that as soon as collar *c* is withdrawn sufficiently so as to permit the segments *b b b* to be opened slightly the springs *d d* will keep 5 the segments away from the wire and pressed against the internal walls of collar *c*. Therefore when the clutch has reached the position as shown in Fig. 4 and the functions of the machine call for the return of clutch to the 10 position shown at Fig. 3 it can be done without any fear of the segments *b b b* sticking on the wire *f*, and in consequence collar *c* being forced upon them before the clutch reaches the extreme position to the left shown 15 at Fig. 3. As soon, however, as the clutch does reach the above position and cannot go any farther by reason of the fixed part *B* then the collar *c*, being still further pushed by the actuating mechanism, is forced upon the segments 20 as far as is required to effectually secure them upon the wire, so that collar *c* will not come off them merely by the effort exerted upon it to move the wire forward or feed it; but the stripping of collar *c* off the segments 25 can only be effected when the latter are in the position as shown in Fig. 4 and cannot go any farther by reason of the fixed part *C* they abut against, so that the actuating mechanism pushes collar *c* yet somewhat farther 30 in order to strip it and leaving the parts in the position shown in said figure, and so the operation is repeated.

Since the closing of clutch in the position shown in Fig. 3 has to be effected when the 35 wire is running, because in the meantime certain cutting operations are performed upon the wire, it is most important to reduce the friction between the stationary and revolving parts employed in transmitting the longitudinal motion to the clutch. It is for this reason that the ball-bearing has been inserted 40 within the housing surrounding collar *c* and on that side of the housing where the greatest pressure is encountered—namely, when 45 closing or compressing the clutch upon the wire.

The two flats shown at *k*, Fig. 2, are for the purpose of turning the nut *h* in the housing *g*.

50 The feed-lever *A* is operated by a cam, and thus would force the lever to assume the same position each time irrespective of the varying thickness of the wire, with the result of straining the lever in the case of the wire being 55 slightly larger in diameter. In order to effectively overcome this difficulty, yet produce the same gripping power on the feed-clutch, even should the wire vary considerably in diameter, the feed-lever *A* is formed in two 60 parts *E F*, as shown in Figs. 8 and 9. The member *E* of the lever is pivoted on studs *l* and is thereby secured to the frame of the machine. One end of it holds the feed-clutch, and on the other end the other member *F* is 65 pivoted at *m* to it. The member *F* has an extension *F'* in the form of a handle, which is merely used for operating the lever by hand

when setting the machine. The member *F*, furthermore, carries a roller *n*, upon which the cam provided for this purpose on the machine 70 acts. The end of lever *F* bears upon a stud *o*, carried in a recess *q* of the lever *E*, said stud being kept outwardly pressed by a spring *p*. A pin *o'*, thrust through the stud outside of the recess, retains the stud in place. The lever *F* is also provided with a recess containing a spring *s*, which exerts force against a bar *t*, forming a connection across the ends of lever *E*. When the cam forces the lever to the right, it imparts the reverse motion to the 80 other end, which carries the feed-clutch, and this movement produces the closing action of the feed-clutch on the wire. The said feed-clutch is forced with its one end against the fixed point *B*, and as soon as it reaches the 85 same and is forced to stop there the lever, continuing its motion, closes the clutch, as by forcing the collar *c* upon it until a certain compression of the members of the clutch upon the wire is reached. As soon as this 90 happens the spring-stud *o* is acted upon by the end of member *F* to such an extent as has been determined upon by the setting of the cam, which acts upon roller *n*. As will be noticed, this spring-stud *o* is situated a considerable distance from the fulcrum of member *F*, whereas point *n* is situated very close to said fulcrum, which is at *m*. Therefore a considerable transmission of power is effected. In one form of machine, for instance, the spring-stud will begin yielding only when a pressure of from one hundred and fifty to two hundred pounds has been exerted at *n*, which has been found ample to sufficiently close the feed-clutch. It will be seen that as 100 soon as feed-clutch has reached point *B* and the collar has been driven as hard upon the segments as the resistance of the spring-stud permits the spring-stud will begin to yield, thereby preventing any excessive further 110 pressure being brought upon the collar of the clutch or any excessive strain being created in the combined levers *E F* by the force of the cam acting upon roller *n*. It will furthermore be seen that a considerable margin 110 of movement is now obtained in the whole lever, although the cam is in a fixed position on the one end and point *B* is a fixed stop on the other end. It is therefore easy to so adjust the cam that each time the feed-clutch 120 is gripping on the wire the spring-stud will be compressed more or less, this action depending entirely upon the wire being above or below its normal diameter. From the moment the spring-stud is yielding it is evident 120 that the pressure which forces the collar upon the segment is practically constant, as it will only increase slightly in proportion to the resistance of the spring, increasing as it is being pressed home.

130 So far the action of the lever in connection with the feed-clutch is explained as above only as far as it refers to the closing of the feed-clutch upon the wire. Now I shall pro-

ceed to describe the other part of the function of this feed-lever—namely, the stripping of the feed-clutch off the wire.

Assuming that the lever and feed-clutch be in the position that the ends of the segments *b* touch point *B*, and assuming that the general functions of the machine require the feeding of the wire to take place, then the cam will act upon roller *n*, forcing it to the left, and thereby forcing the other end of the combined lever with the feed-clutch to the right until point *C* is reached by the other ends of the segments, when the feeding of the wire will be effected as far as the wire itself is concerned. The statement previously made as to the difficulty caused by the varying diameter of the wire as far as it refers to the closing of the clutch on the wire is to a certain extent applicable also to the stripping of the feed-clutch upon the wire. It is clear that if collar *c* by virtue of the varying diameter of the wire occupies different positions on the tapered segments the right-hand end of such segments could not be brought home to point *C*, as is most important they should be. In order to effect perfect regularity and reliability of this function of the feed, the spring *s* is provided. Said spring *s* is a weak one compared to the spring *p* and has for its object to keep the right-hand end of the segments and point *C* in positive touch with one another prior to the collar being stripped from the segments. It is important for the purpose of obtaining the greatest accuracy that as soon as the feed of the wire has taken place and these points are in touch with one another they remain so, because at the interval when the functions of the machine call for the feeding of the wire all clutches or other holding devices which hold the wire when in operation are open, and therefore the wire is perfectly free to be displaced from its true position by concussions, vibrations, &c. Following the movement of the combined levers it will be noticed that as soon as these points are in touch and while the cam is still forcing roller *n* to the left the spring *s* will begin to operate, allowing for a sufficient margin of movement, although the cam is in a fixed position and point *C* is in a fixed position, so that the collar *c* will be apt to take different positions upon the tapered segments *b*, according to whether the wire is above or below its normal diameter. It is easy to see that the cam can be so adjusted as to provide a sufficient excess of movement so as to compensate for the varying positions longitudinally of the collar *c*. The functions of the cam provide that the right-hand end of the segments and point *c* be kept in close touch, but without force except by that exerted by the pressure of spring *s*, until a certain movement has been effected in the machine, and therefore the wire is locked in its longitudinal position, and immediately after that the cam gives a further movement to the left to roller *n*, which movement, however, is in ex-

cess of the movement to member *F*, as provided at point *s*, and therefore the combined members *E* and *F* act at once as if they were one solid body, and hence the full pressure exerted at *n* to the left is brought to bear at the other end to the right, causing by positive force collar *c* to be stripped as far as is necessary off the segments. This last movement being effected, the cycle of operations can then again begin.

What I claim is—

1. In a device for feeding wire a series of segments having their interior faces adapted to fit on the wire, grooves in said interior faces, springs in said grooves adapted to keep said segments out of holding contact with the wire, a groove in the outer surfaces of the segments, a spring in such groove adapted to hold the segments loosely together and means for closing said segments on the wire. 80

2. In a device for feeding wire a series of segments having their interior faces adapted to fit on the wire and their exterior faces tapered, a collar having an interior tapered surface corresponding to the tapered surface of the segments, a row of balls outside of such collar, means carried by the collar to form an abutment for the balls on one side, and a housing for the balls, and means carried by the housing for forming an abutment for the balls on the other side. 90

3. In a device for feeding wire a series of segments having exterior tapered surfaces for gripping the wire, a collar having an interior surface adapted to fit on the tapered surfaces of the segments a series of balls around said collar means for carrying and supporting same thereon, and means for forcing the collar onto the tapered segments, and withdrawing same, such balls acting as a rolling bearing between such means and a fixed part of the collar during the forcing operation. 100

4. In a device for feeding wire, a series of segments having their interior faces adapted to fit on the wire and their exterior faces tapered, a collar having an interior tapered surface corresponding to the tapered surfaces of the segments, a flange carried by the collar a row of balls next to said flange, also carried by the collar, a housing inclosing said balls and flange, means carried by the housing for holding the collar in one position longitudinally, and a nut also carried by the collar against which the balls abut and adapted to prevent the collar moving in the other direction longitudinally, and means for moving the housing and collar on the segments. 110

5. In a device for feeding wire, a clutch adapted to grip the wire, a pivoted lever for carrying same, a part pivoted to such lever, means for operating such part, and a spring interposed between the free end of such part and the lever, such spring adapted to allow the lever and its pivoted part to act together but to yield when an excess pressure is brought to bear upon the operated part. 125

6. In a device for feeding wire, a clutch

adapted to grip the wire, a pivoted lever for carrying same, a part pivoted to such lever, means for operating such part, a spring interposed between the free end of such part and the lever, and a second spring also interposed between the parts at a point nearer the pivotal point of same, said springs adapted to allow the lever and its operated part to act as a whole under normal conditions, but to yield in either direction of its operation under strain.

7. In a device for feeding wire, a clutch adapted to grip the wire, a pivoted lever for carrying same, a second lever pivoted about one end of same, means for operating such

second lever, a spring-stud carried by the first lever on which the free end of the second lever is adapted to press, and a spring interposed between the two levers at a point nearer the pivotal point of same, substantially as described.

In testimony whereof I have hereunto set my hand in the presence of two subscribing witnesses.

ERNST GUSTAV HOFFMANN.
